UNITED STATES PATENT OFFICE.

HAROLD E. YARROW, OF GLASGOW, SCOTLAND.

STORAGE OF OIL-FUEL IN VESSELS.

1,296,450.

Specification of Letters Patent.

Patented Mar. 4, 1919.

Application filed October 30, 1917. Serial No. 199,315.

To all whom it may concern:

Be it known that I, HAROLD EDGAR YARROW, a subject of the King of Great Britain, residing in Glasgow, Scotland, have invented certain new and useful Improvements Connected with the Storage of Oil-Fuel in Vessels, of which the following is a specification.

In certain classes of vessels using oil fuel, 10 more particularly destroyers, it is important to increase the storage capacity for the oil beyond that usually provided. If this additional storage space were provided at the ends of the vessel the amidships part would 15 require to be very considerably strengthened in order to stand the stresses set up when the ends were raised out of the water in a heavy sea.

In addition to the tanks usually provided, 20 other oil tanks may be placed amidships underneath the boilers throughout the stokehold compartments. This disposition of the weights reduces the stresses acting on the vessel in a sea-way and thereby enables material to be economized and a saving in weight to be effected.

In order, however, to prevent the oil tanks underneath the boilers from being raised to 25 too high a temperature by the heat radiated from the brick pans at the bottom of the furnaces, according to the invention, a grid of small tubes through which water circulates is placed between a brick pan and the tank below it.

30 In the accompanying drawing, which shows an example of the invention as applied to a destroyer, Figure 1 is a cross section of the vessel taken in front of one of the boilers; Fig. 2 is a longitudinal section 35 through a water tube boiler.

A is a steam drum, B water drums, C superheater tubes, D are oil tanks underneath the boilers, E is a grid formed of small tubes, through which water circulates.

Copies of this patent may be obtained for five cents each, by addressing the "Commissioner of Patents. Washington, D. C."

The grid is placed between the bottom 45 of the brick pan and the oil tanks and may extend, as shown, across the full width of the tanks, or only across the central part of this width.

The water tubes E are fitted into headers 50 F, the inlets to which are shown at G and the outlets at H. The water supply to the grid may either be the feed suction, in which case the feed water would be slightly heated, or an independent supply of water may be 55 caused to circulate through the grid by a pump.

Having now fully described the nature of my said invention and the best means I know of carrying the same into practical effect, I 60 claim:—

1. In a ship provided with boilers fired by oil fuel, oil tanks placed below the boilers, grids of tubes placed between the boilers and the tanks, headers connected to the tubes 65 at opposite ends thereof, a water inlet at one set of headers and a water outlet at the opposite headers, and means for circulating the water through said tubes.

2. In a ship provided with boilers fired 70 by oil fuel, oil tanks placed below the boilers, grids of tubes placed between the boilers and the tanks, headers connected to the tubes at opposite ends thereof, a water inlet at one set of headers and a water outlet at the opposite headers, and means for circulating 75 the feed water to the boiler through said tubes.

In testimony whereof I have signed my name to this specification in the presence 80 of two subscribing witnesses.

HAROLD E. YARROW.
